UNITED STATES PATENT OFFICE.

FRANK H. MORSE, OF ROCKFORD, ILLINOIS.

HUB.

No. 833,407.

Specification of Letters Patent.

Patented Oct. 16, 1906.

Application filed November 3, 1904. Renewed November 18, 1905. Serial No. 288,062.

To all whom it may concern:

Be it known that I, FRANK H. MORSE, a citizen of the United States of America, residing at Rockford, in the county of Winnebago and State of Illinois, have invented certain new and useful Improvements in Hubs, of which the following is a specification.

My invention relates to certain new and useful improvements in hubs for automobile-wheels, consisting in certain novel features described, and fully illustrated in the hereto accompanying drawings, in which—

Figure 1 shows my said new hub in central vertical section, but whereof certain parts are shown in elevation. Fig. 2 shows the universal joint in elevation revolved axially quarter way round from the position shown in Fig. 1. Fig. 3 shows an outer end view of the outer shaft end and its arms seen in the direction of the arrow 3 in Fig. 1. Fig. 4 shows the face-plate E of the outer end of the hub in plan view.

Like reference-letters denote like parts throughout.

The object of my invention is to produce an automobile-wheel hub and wheel which shall respond quickly and easily to the action of the steering-wheel, and thereby give easier and greater control over such vehicles. To attain said desirable ends, I construct my said new device in substantially the following manner, namely:

In the drawings the axle-tube (shown at A) forms a part of the vehicle-frame, within which revolves the wheel-driving shaft H. Spreading arms B, one vertically above the other, are secured to the outer ends of said tube, and their outer free ends enter into a short hollow steering-axle C, pivoted to the ends of said arms, as shown. Said axle C is provided with a steering-arm C', extending toward the opposite wheel, by means of which, with suitably-connected attachments, the direction of the wheel plane can be changed for steering purposes. The wheel-hub D turns on said axle C on ball-bearings d of well-known construction, which hold the hub to its place on said axle, and a face-plate E, secured by screw-bolts to the outer end d' of the hub D, provided with a central hole e having corresponding sides parallel to the sides of the shaft end F, which enters said hole in a close fit, but which still permits free reciprocal motion to the shaft in said plate. Said shaft end F and hole in said plate are preferably of four-sided polygonal form.

The opposite or inner end of the shaft F is provided with a pair of arms F', which embrace the opposite sides of an articulator or block G and are secured thereto by pivots or pivot-screws, as shown, and a similar pair of arms H', set in a plane at right angles to the plane of the arms F' and forming a part of one end of the shaft H, also reach over the face of said block and are secured to it by pivot-screws, which thus forms the well-known universal joint which articulates on a plane transverse to the axis of the shaft H, and which (said plane) is situated in the axis of the four pivot-screws shown in the ends of the arms F' and H' and which (said plane) is made to coincide with the central plane of the wheel on said hub, and said wheel plane is furthermore to coincide with the axes of the pivots which connect the hub C to the arms B, whereby is obtained an easy and perfect control of every wheel provided with this hub mechanism.

A nut f on the end of the shaft F and set on its shoulder f' leaves a short space for play-room for said shaft between said nut and the face-plate E.

The axial revolution of the shaft H is transmitted to the part of shaft F by means of the intervening universal joint here shown, and the shaft F revolves the plate E, which is fastened to the hub D, and said hub D rotates on the short axle C on the ball-bearings d, said hub and axle-bearing connected and held together as shown here or held in any other suitable manner.

As the longitudinal adjustment of the ball-bearings on the short steering-axle is made in the usual way, as shown in the drawings, it becomes necessary to allow the same adjustment to the face-plate on the shaft F. Said adjustment is accomplished by making the square or polygonally-sided part F longer than the thickness of the face-plate would require as indicated by the short space between the face-plate and the nut f. Said freedom of longitudinal adjustment of the face-plate on said shaft also affords the opportunity for whatever short reciprocal motion there may be required by the revolution of the universal joint whenever a wheel is turned or steered in an angle to the direction of motion, whereby in both cases is given relief to all strain there might occur to any of said parts.

The outer end of the steering-axle C is screw-threaded, and on it is mounted a cone

or ballway d^2 , and it is pushed and held to its place by means of a pair of threaded adjusting-rings $d^3 d^4$, which are locked to place by screws d^5 in the following manner—namely, 5 the inner ring d^3 is screwed to its desired place against the cone-ring d^2 and is followed by its locking-ring d^4 . Said rings are provided with screws d^6 , of which the spacing coincides axially, which necessarily separates 10 said rings unless when the one is driven on the other, the screw-holes happen to coincide; otherwise said rings are separate. Said threaded adjusting-rings $d^3 d^4$ are then pressed toward each other by means of said 15 screws d^5 , whereby is secured a pressure and friction on the threads of said ring which thereby locks them to their place.

What I claim is—

1. The combination with an armed axle- 20 tube and an armed steering-axle pivoted to said arms, of a hub on said axle, a face-plate on said hub, a polysided opening in said plate, a correspondingly-sided shaft in said opening, means to limit the longitudinal motion of 25 said shaft in said plate, a universal joint to said shaft, said joint centered in the central wheel plane, and a driving-shaft to said joint.

2. The combination with an armed axle- 30 tube and an armed steering-axle pivoted to said arms, of a hub on said axle, a face-plate

on said hub, a polysided opening in said plate, a correspondingly-sided shaft in said opening, a shoulder and a nut on said shaft, a space between said plate and nut, a universal joint to said shaft, and a driving-shaft to said joint. 35

3. The combination with a hollow two- 40 armed axle-tube, and an armed steering- axle, pivoted on said arms, of a hub with a face-plate, a polysided opening in said plate, a correspondingly-sided shaft in said opening, 45 said shaft reciprocable in said opening and extending beyond the face of said plate, a nut on said shaft and a universal joint and a driving-shaft to said shaft.

4. The combination with an axle-tube and 45 a threaded steering-axle pivoted to said tube, a hub and ballways and balls on said axle, a face-plate on said hub, a polysided opening in said plate, a correspondingly-sided shaft in said opening, and a universal joint to said 50 shaft, of locking mechanism, relatively adjustable, to lock the hub to said axle.

In witness whereof I have signed the above application for Letters Patent, at Rockford, in the county of Winnebago and State of Illinois, this 31st day of October, A. D. 1904.

FRANK H. MORSE.
